[57] CLAIM

The ornamental design for a batting practice training box, as shown and described.

DESCRIPTION

FIG. 1 is a perspective view of the batting practice training box showing our new design;

FIG. 2 is a top plan view thereof;

FIG. 3 is a bottom plan view thereof;

FIG. 4 is a front elevational view thereof, the rear being plain and unornamented;

FIG. 5 is a side elevational view thereof, taken from the right side of FIG. 2;

FIG. 6 is an exploded perspective view thereof.

FIG. 4

FIG. 1

FIG. 3
